ATTORNEY.

UNITED STATES PATENT OFFICE.

PETER MOHRDIECK, OF OAKLAND, CALIFORNIA, ASSIGNOR TO THE STANDARD GAS ENGINE COMPANY, OF OAKLAND, CALIFORNIA, A CORPORATION OF CALIFORNIA.

INTERNAL-COMBUSTION ENGINE.

1,306,496.

Specification of Letters Patent. Patented June 10, 1919.

Application filed July 25, 1917. Serial No. 182,768.

To all whom it may concern:

Be it known that I, PETER MOHRDIECK, a citizen of the United States, residing at Oakland, in the county of Alameda and State of California, have invented certain new and useful Improvements in Internal-Combustion Engines, of which the following is a specification.

This invention relates to improvements in internal combustion engines and more particularly to means associated therewith whereby fuel having a higher point of vaporization than commercial gasoline may be efficiently used in the engine.

One of the objects of the present invention is to provide the cylinders with an air jacket in which a preliminary heating of the air to the carburetor takes place, the passage of air therethrough serving also to assist in cooling the cylinders.

Another object of the invention is to provide auxiliary exhaust ports through which a portion of the burnt gases are discharged thereby relieving the regular exhaust valves and more quickly reducing the pressure in the cylinders. A still further object of the invention is to provide a type of heater in which the air to the carburetor is caused to take up a certain amount of heat before passing the spray nozzle, and after passing through the latter, an additional amount of heat is communicated thereto. And finally I provide means for drawing off any vapor, combustible or otherwise, which accumulates within the crank case.

With these and other objects in view, the invention consists of certain novel features of construction, combinations and arrangements of parts hereinafter described and more specifically pointed out in the appended claims; it being understood that changes in form, proportion, size and minor details of construction within the scope of the claims may be resorted to without departing from the spirit of the invention or sacrificing any of the advantages thereof.

Referring to the accompanying drawing forming a part of the specification,

Figure 1— is a view in section through an engine cylinder and heater constructed in accordance with my invention.

Fig. 2— is a view in horizontal section of the same.

Fig. 3— is a view in rear elevation of the

improved heater showing a carburetor partly in section attached thereto.

Fig. 4— is an enlarged sectional view on the line 4—4, Fig. 1.

Fig. 5— is a detail sectional view on the line 5—5, Fig. 2.

In the following specification I have shown my invention as being applied to a pair of engine cylinders, cast *en bloc* but it will be understood that by suitable modifications in design the invention is equally applicable to a single cylinder or to any number of cylinders.

Referring to corresponding parts of the several views by the same numerals of reference, 1 and 2 denote engine cylinders each having an exhaust valve 3, an intake valve of similar construction which is not shown, and the usual water jacket 4. The piston is designated by 5 and is here shown at the lowest point of its travel while 6 denotes the upper portion of the crank case to which the cylinder is attached in any preferred manner.

The water jacket 4 extends to a point below the lowermost point of piston travel and below the water jacket is an air jacket 7. This jacket is provided on one side of the cylinder with air holes 8 while on the opposite side is an exit port 9, and I have also provided, at the lower portion of the air jacket, an opening 10 which communicates with the interior of the crank case 6. Above the port 9 are ports 12 extending from the interior of the cylinders 1 and 2 through the water jacket to the outside thereof, these ports being so positioned that they are just uncovered by the upper end of the pistons when in their lowermost positions.

Attached to the walls of the engine jacket is a valve casing denoted generally by 14, this casing being of sufficient width and depth to cover the exhaust ports 12 and the air port 9. In this casing is an upper chamber 15 and a lower chamber 16, the former communicating with the exhaust ports and the latter with the air ports.

Pivotedly mounted in the side walls of the casing 14 and in suitable lugs 17, are rods 18, to which is attached a swinging check valve 19. These rods are continued through the casing and have attached on the outside thereof arms 50 to the outer end of which is attached coil springs 51.

Extending outwardly from the body of the valve casing are lugs 52 through which pass pins 53. To one end of these pins are attached the other end of the springs 51 while on the other end, on the opposite sides of the lugs, are adjusting screws 54. By so arranging the springs, the tension thereof may be adjusted to regulate the amount of pressure required to open the valve 19.

10 This, in turn, will govern the amount of exhaust which passes through the ports 12 and, consequently, the amount of heat imparted to the air passing through the heater. This arrangement of the springs also prevents them losing their temper due to excessive heat which would be the case if they are placed within the casing or positioned closely to the sides thereof.

Centrally disposed openings 23 and 24 are 20 provided in the front wall of casing 14 from chambers 15 and 16, respectively, and on each side of opening 23 are other openings 21 into chamber 15, these openings being closed by removable plates 22 which thereby 25 permit inspection and adjustment of the valves 19.

Attached to the front wall of the casing 14 is the improved heater denoted generally by 25, and which consists of the substantially rectangular body portion 26 having at the upper end a neck 27 at right angles thereto. The latter is flanged for attachment to the casing 14 and has passages 31 and 32 which align with openings 23 and 24. The body 26 is divided by the wall 28 into two almost equal chambers denoted by 29 and 30. The upper end of chamber 29 communicates through passageway 31 with the chamber 15 in the valve casing 14, while 35 the upper portion of chamber 30 communicates through the passageway 32 with the chamber 16. It will be noted that passageway 32 is curved to the outside of the neck 27 and then upwardly as shown at 33 to enable it to enter at the top of the chamber 30.

Within the chamber 29 is a tubular member 34 having its upper and lower ends formed in the upper and lower walls of the heater. This member forms a straight passageway 35 which, on its upper end, is in communication with the interior of the intake manifold 36 while on its lower end is in communication with the outlet opening of the carburetor 49.

55 Extending centrally across chamber 30 from the division wall 28 to the opposite wall of the chamber is an irregularly shaped portion 41 which is hollow, the opening 43' therethrough communicating on the 60 one end with the chamber 29 and on the other end with the opening 42 to which is attached the flange end of the exhaust pipe 43. The portion 41 extends neither to the top nor bottom of the casing 26 whereby a 65 passageway is provided on all sides there-

of except where it is joined to the division wall 28 and to the wall adjacent the opening 42.

The bottom of the casing 26 is provided with an opening 44 which communicates 70 with the carburetor intake 45, and the front of chamber 29 has an elongated opening 58 that is closed by the removable plate 59 and which gives access to the chamber 29 and opening 43'.

In the side walls of the chamber 30 near the bottom thereof I provide openings 55 and a valve plate 56 for more or less closing the same. In this manner outside cool air may be, if desirable, mixed with the heated air before it enters the carburetor. An adjustment of the amount of air drawn through the carburetor is secured by some form of valve such as the usual butterfly valve illustrated at 57.

85 In use, when the intake valve is open and the piston is on its down stroke, a suction is created in the intake manifold 36. This draws air through the openings 8 which circulates around the cylinder walls and thus 90 receives a preliminary heating, and at the same time, assists in cooling the cylinder. This air passes from the air jacket 7 through the chamber 16 in the valve casing, 95 through passageways 32 and 33, then down through chamber 30 on the two sides of the portion 41 into the carburetor intake 45 and past the spray nozzle 60. During this time, the air which was first heated by the walls 100 of the cylinder receives an extra increment of heat when it passes over the heated surfaces, especially that of the portion 41. After passing the spray nozzle 60 the fuel laden air is drawn through the passage 35, 105 the wall of which is in contact with the hot incoming gas where it is further heated so that any spray is thoroughly vaporized and passes into the cylinder as vapor instead of minute globules of liquid.

110 As heretofore explained, the exhaust port 12 is merely auxiliary to the regular exhaust valve. This port is uncovered by the piston at the end of the expansion stroke and the residual pressure in the cylinder is sufficient 115 to open the swinging check 19 whereby a portion of the hot burnt gases are discharged through port 12, the chamber 15 and passageway 21. These gases then pass downwardly around the tubular division wall 34 and from there through the flat passageway 120 43' in the portion 41 and finally out through opening 42 into the exhaust pipe 43.

125 It will thus be noted that the incoming hot gases first communicate their heat to the wall 34 through which the vaporized fuel is passing after leaving the carburetor so that a high degree of heat may be imparted to these gases without unduly heating the parts of the carburetor. A portion of air which passes through this device is also drawn 130

through the opening 10 from the crank case the amount thereof depending on the tightness of the latter.

The use of the check valves 19 will now 5 be readily apparent as when the piston reaches the lowest point of the suction stroke, a vacuum still remains in the cylinder and if it were not for these valves, a portion of the unburnt gases previously 10 dispersed into the heater would be drawn back into the cylinder. These valves prevent such action, the suction plus the tension of the springs 51 effectively holding them closed, and yet the force exerted by the springs may be 15 made so light that it requires very little pressure to open the valves during the exhaust period. On the other hand if less heat is desired in the air passing through the heater, then the tension of the springs may be increased 20 resulting in a smaller opening of the valves and a decreased flow of hot gas.

While I have shown the preferred embodiment of my invention in which the heater is attached to an auxiliary exhaust port, it will 25 be readily apparent that by slight modification the heater might be attached direct to the ordinary exhaust manifold and that air could be drawn directly from the atmosphere instead of first through an air jacket.

Having thus described my invention, I claim as new and wish to cover by Letters Patent:—

1. The combination with an internal combustion engine cylinder having an air jacket, 35 of a fuel heater having an air passageway and a burnt gas passageway with common division walls, the ingress end of said gas passageway communicating with an exhaust port in said cylinder, means for regulating 40 the amount of gas flowing through said gas passageway, and the ingress end of said air passageway communicating with said air jacket, an auxiliary air intake for admitting air to said air passageway intermediate its 45 ends, and a carbureter interposed in said air passageway intermediate the ends thereof.

2. The combination with an internal combustion engine cylinder having an exhaust port adapted to be uncovered by the piston 50 near the end of its out stroke, a fuel heater having two adjacent non-communicating chambers, a cylindrical tubular member having an air passageway extending longitudinally through the first of said chambers, a 55 flat, tubular member extending transversely across the second of said chambers and having a gas passageway communicating with said first chamber and the atmosphere, a carbureter having the end of its passageway 60 connected to one end of said cylindrical tubular member and one end of said second chamber, and a laterally extending neck on said body having two passageways one of which 65 communicates with said exhaust port and said first mentioned chamber and the

other of which communicates with the atmosphere and said second chamber.

3. An explosive engine, the combination with an engine cylinder having an exhaust port, an intake opening and a carbureter, a 70 heater comprising a body portion having integral walls forming two chambers, an integrally formed tubular member extending longitudinally through one of said chambers and communicating at one end with 75 said intake opening and at the other end with the egress end of said carbureter, said chamber communicating with said exhaust port, an integrally formed flat, tubular sleeve extending transversely through the 80 second of said chambers and having a passageway communicating with said first mentioned chamber and with the atmosphere, said second chamber having an air intake opening on one end and an egress opening 85 on the other end communicating with the air intake of said carbureter.

4. The combination with an internal combustion engine cylinder having an exhaust port adapted to be uncovered by the piston 90 near the end of its out stroke, a fuel heater having two adjacent non-communicating chambers, a cylindrical tubular member having an air passageway extending longitudinally through the first of said chambers, a 95 flat, tubular member extending transversely across the second of said chambers and having a gas passageway communicating with said first chamber and the atmosphere, a carbureter having the end of its passageway 100 connected to one end of said cylindrical tubular member and one end of said second chamber, a laterally extending neck on said body having two passageways one of which communicates with said exhaust port and said first mentioned chamber and the other of which communicates with the atmosphere and said second chamber, a check valve in 105 said passageway communicating with said exhaust port, and spring means for adjusting the amount of opening of said valve.

5. A device of the character described comprising the combination with a gas engine cylinder having an exhaust port, valve casing attached to said cylinder and having a chamber communicating with said port, a heater attached to said casing having two adjacent non-communicating passageways, one for air and one for gas, the ingress end of said gas passageway communicating with the chamber casing, a check valve in said casing adjacent said port, and spring means for regulating the movement of said check valve and the consequent flow of gas through 115 said gas passageway.

6. The combination with an internal combustion engine cylinder having an exhaust port adapted to be uncovered by the piston near the end of its out stroke, a fuel heater having two adjacent non-communicating 120

chambers, a cylindrical tubular member having an air passageway extending longitudinally through the first of said chambers, a flat, tubular member extending transversely across the second of said chambers and having a gas passageway communicating with said first chamber and the atmosphere, a carburetor having the end of its passageway connected to one end of said cylindrical tubular member and one end of said second chamber, said first mentioned chamber having an air intake opening extending through its walls, an adjustable valve for regulating the flow of air through said opening, a laterally extending neck on said body having two passageways one of which communicates with said exhaust port and said first mentioned chamber and the other of which communicates with the atmosphere and said second chamber, a check valve in said passageway communicating with said exhaust port, and springs means for adjusting the amount of opening of said valve.

7. An air heater comprising a hollow body substantially parallelepiped in shape, a division wall extending longitudinally through said body and forming two substantially equal non-communicating chambers, an integrally formed tubular member having an air passageway extending longitudinally through one of said chambers, an integrally formed flat tubular member extending from said division wall transversely across the second of said chambers and having a passageway communicating with said first chamber, and a laterally extending neck adjacent one end of said body having passageways communicating with the corresponding ends of said chambers.

8. In a heater of the class described comprising in combination with a gas engine cylinder having an exhaust port and an air jacket, a body portion having circuitous exhaust gas and air passageways separated by heat transmitting division walls and having ingress and egress openings thereto, a

valve casing interposed between said heater and said cylinder and having a gas chamber in communication with said exhaust port and the ingress opening of said gas passageway, and having an air chamber communicating with said air jacket and the ingress opening of said air passageway, and a spring operated valve in said gas chamber for closing said exhaust port. 50

9. In a heater of the class described comprising in combination with a gas engine cylinder having an exhaust port and an air jacket, a body portion having circuitous exhaust gas and air passageways separated by 60 heat transmitting division walls and having ingress and egress openings thereto, a valve casing interposed between said heater and said cylinder and having a gas chamber in communication with said exhaust port and 65 the ingress opening of said gas passageway, and having an air chamber communicating with said air jacket and the ingress opening of said air passageway, a valve in said gas chamber for closing said exhaust port, a 70 spring for holding said valve closed and means for adjusting said spring so as to regulate the amount of exhaust past said valve.

10. In a device of the character described 75 comprising the combination with a gas engine cylinder, having a mechanically operated exhaust valve, a piston and an exhaust port adapted to be uncovered by said piston near the end of its out stroke of a heater 80 having two adjacent non-communicating passageways, one for air and one for hot gas, attached to said cylinder, the ingress end of said gas passageway terminating in an enlarged chamber, a valve pivotally 85 mounted in said chamber for closing said exhaust port and adjustable means for regulating the pressure of said valve against its seat.

In testimony whereof I affix my signature. 90

PETER MOHRDIECK
